LUTHER L. KNOX, OF PITTSBURGH, PENNSYLVANIA, AND GEORGE L. DANFORTH, JR., OF CHICAGO, ILLINOIS, ASSIGNORS TO BLAW-KNOX COMPANY, OF PITTSBURGH, PENNSYLVANIA, A CORPORATION OF NEW JERSEY.

WATER-COOLED DOOR-FRAME.

1,282,861.

Specification of Letters Patent. Patented Oct. 29, 1918.

Application filed June 28, 1916. Serial No. 106,495.

To all whom it may concern:

Be it known that we, LUTHER L. KNOX, residing at Pittsburgh, in the county of Allegheny and State of Pennsylvania, and 5 GEORGE L. DANFORTH, Jr., residing at Chicago, in the county of Cook and State of Illinois, both citizens of the United States, have invented certain new and useful Improvements in Water-Cooled Door-Frames 10 for Heating and Melting Furnaces, of which the following is a specification.

The present invention has reference to improvements in water-cooled door frames for heating and melting furnaces, particularly those furnaces whose operations are attended with unusual hard service and that, therefore, require a door frame constructed to resist the severe service with the least chance of developing water leaks through 20 cracks, seams or rivet holes.

To those familiar with the art it is known that there are now in general use three types of water-cooled door frames: 1st. Those made of cast iron or cast steel, having within 25 and extending down the legs of the frame a space for the cooling water. Such frames, being made of cast material, are least able of all water-cooled frames to stand the hard service, for the walls thereof being exposed 30 on one side to the cold water and on the other side to the high temperature of the furnace are subjected to expansion and contraction strains too great for the strength of the material, and after a short service 35 develop cracks and water leaks that make it necessary to discard the frame. This inherent defect cannot be overcome, for if the walls are strengthened by being made thicker the strains become greater on account 40 of the greater difference in temperature of one side of the walls compared to the other side. 2nd. Those frames made of rolled steel plates fabricated with rivets. Such frames do not crack as do those made of 45 cast iron or cast steel, but the rivet holes very quickly cause water leaks and these frames do not endure any longer than do those of cast material. 3rd. Those frames made of rolled steel plates fabricated by 50 welding together the plates instead of riveting. Such frames are giving good service and enduring much longer than those previously mentioned, but there are some furnaces where the operation is unusually se-

vere and where the door frames are subjected to a considerable pounding by the heavy machine used to charge the material into the heating or melting furnace, and it is for such work that there is needed a door frame of very heavy construction that can be made at a reasonable cost.

The object of this invention is, therefore, to provide a water-cooled door frame that can be made at a reasonable cost, yet so substantial in its construction that it will successfully resist not only the strains of expansion and contraction but also the heaviest punishment from the furnace charging machine.

Figure 1 is a front elevation of the water 70 cooled frame, a part being shown in section.

Fig. 2 is a sectional view taken on line II-II of Fig. 1.

The water-cooled frame 2 constituting this invention is made of a slab of rolled steel, 75 having substantially the same over-all dimensions as the finished door frame. There is then cut out the door way 3. This is preferably done by burning out with a gas torch and then finishing on a cutting machine. 80 The interior of the slab is then removed by drilling out same, thus forming in the frame a chamber or space 4 for containing the cooling water. This drilling is done from the top of the frame and is done by 85 first running the drill down the legs of the frame and then marking out the intervening space into drill spaces that overlap one another, so that the walls of steel surrounding the cooling water are corrugated and thereby strengthened. Having marked out the 90 drill spaces, alternate ones are first drilled so that the drill is entirely surrounded by the steel; then as the remaining spaces are drilled the drill is unsupported on two opposite sides and supported on the remaining sides opposite to one another. In this way the opposite pressures on the drill are equal and the drill will follow a straight line. Each hole is drilled to a depth measured to 100 leave the desired thickness of steel wall forming the arch of the doorway. There is then welded on the open top of the door frame a plate cover 5, having a pipe connection for discharging the water and a pipe 105 for supplying the water. This supply pipe has several branches, two extending into the two legs of the frame and at least one to

supply cold water to the arch of the doorway. The water from the legs and that from the arch circulate upward to the discharge pipe.

5 It can be seen that in this way there is provided a door frame of very heavy and rigid construction, the walls of which are of rolled steel and corrugated by the drilling process; also, those walls exposed to the 10 service are absolutely seamless, the entire frame being so except at the top where there is only the water pressure to withstand.

At the bottom of each leg there is provided an extension or foot 6 by means of 15 which the frame is fastened down to the fore plate, and there are also provided the independent check plates of rolled or cast steel that are placed in front of the door frame and attach to the furnace buckstaves, 20 thus holding the frame from this side while the furnace bottom, brick walls and roof channel hold it from the opposite side.

Any suitable means may be provided for maintaining a circulation of water within 25 the frame. For this purpose we have shown the circulating pipes 7 having legs 7^a which extend downwardly into the water space at each side of the door opening.

Having described the invention, its manufacture and usefulness, what we claim as 30 novel is:

1. As a new article of manufacture, a chambered furnace door frame made from

a rolled steel slab, said frame having plane outer surfaces and corrugated walls within 35 the chamber, substantially as described.

2. As a new article of manufacture, a chambered furnace door frame made from a rolled steel slab, and having a doorway therethrough with legs at each side of the 40 doorway extending downwardly from the bottom of the frame, said frame having plane outer surfaces and corrugated walls within the chamber, there being a recess extending downwardly in each of said legs 45 communicating with the chamber, substantially as described.

3. As a new article of manufacture, a chambered furnace door frame made from a rolled steel slab, and having a doorway 50 therethrough with legs at each side of the doorway extending downwardly from the bottom of the frame, said frame having plane outer surfaces and corrugated walls within the chamber, and a cover secured to 55 the upper end of said door-frame and forming a closure for the chamber, substantially as described.

In testimony whereof, we have hereunto set our hands.

LUTHER L. KNOX.
